Primary Examiner — Paula Allen Greene(74) *Attorney, Agent, or Firm* — Andon IP Legal(57) **CLAIM**

I claim the ornamental design for a noise-cancelling headphone, as shown and described.

DESCRIPTION

FIG. 1 is a perspective view of a noise-cancelling headphone showing my new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines depict portions of the headphone that forms no part of the claimed design.

1 Claim, 6 Drawing Sheets(56)
